UNITED STATES PATENT OFFICE.

THOMAS J. ROGERS, OF BARNESVILLE, OHIO.

DESIGN FOR A TABLE.

SPECIFICATION forming part of Design No. 22,993, dated December 26, 1893.

Application filed October 19, 1893. Serial No. 488,647. Term of patent 14 years.

To all whom it may concern:

Be it known that I, THOMAS J. ROGERS, a citizen of the United States, residing at Barnesville, in the county of Belmont and State of Ohio, have invented and produced a new and original Design for Work or Kitchen Tables, of which the following is a specification, reference being had to the accompanying drawing, in which—

10 The figure represents a perspective view of a table embodying my design.

The design for the table comprises a plain rectangular top, four corner legs, and underneath the table top at the front an ornamental board having one leg depending centrally

from it, all of which will be readily comprehended from the drawing, which will enable others to reproduce tables of my design.

Having thus described my design, what I desire to secure by Letters Patent therefor is— 20

The design for a table, substantially as herein shown and described.

In testimony that I claim the foregoing as my own I affix my signature in the presence of two witnesses.

THOMAS J. ROGERS.

In presence of—

A. ROGERS,
JAMES CASSELL.
